(57) **CLAIM**

The ornamental design for a candle stand, as shown and described.

DESCRIPTION

FIG. 1 is a perspective view of the candle stand of the present invention;

FIG. 2 is a side view of the candle stand as shown in FIG. 1;

FIG. 3 is a top view of the candle stand; and,

FIG. 4 is a bottom view of the candle stand.

Note that each of the four sides of the candle stand is identical and therefore each side is not shown separately.
